Primary Examiner — Philip S Hyder*Assistant Examiner* — Ramzi Almatrahi(74) *Attorney, Agent, or Firm* — Haynes and Boone, LLP(57) **CLAIM**

The ornamental design for a marine radar housing, as shown and described.

DESCRIPTION

FIG. 1 is a top-front-right perspective view of a marine radar housing embodying the new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines depict portions of a marine radar housing in which the design is embodied that form no part of the claimed design.
